SHOE CLEANING DEVICE

Frank B. Williams, Chicago, Ill.

Application March 5, 1938, Serial No. 194,042

1 Claim. (Cl. 15—265)

This invention relates to an improved device adapted for convenient shoe cleaning, and for the holding of a brush or polisher, by providing a compact and foldable rest for the foot while 5 cleaning a shoe and a pocket for the brush.

It has been found highly desirable to provide a firmly mounted and convenient shoe rest device whereby shoes may be brushed, cleaned or touched up in the home or hotel room or such 10 other place, at a point where it will be readily available, not take up much space, be of collapsible construction, be adapted to receive and position the polishing instrument such as a brush where it can be readily retained and at all 15 times conveniently preserved and ready for use, and at the same time be ever present in a fixed position, so that the operation will always be carried out at the same predetermined place.

Other objects relate to economy, novelty of 20 construction, and detailed arrangement of parts as will be apparent from consideration of the drawing and the following specification wherein—

Fig. 1 is a side elevation of my improved device folded up horizontally and out of use, and 25

Fig. 2 is a side elevation thereof at its unfolded and operative position.

Fig. 3 is a transverse section at the line 3—3 of Fig. 2.

Fig. 4 is a plan view of my device in its unfolded operative position.

Referring to the drawing 10 indicates a base adapted for affixing the device in a vertical position to a suitable mounting support such as a 35 door or the wall 11, by means of a series of screws 12 which pass through the base. This base may be stamped from a single piece of metal so as to comprise the arms 13 which extend integrally therefrom and perpendicularly thereto in spaced-apart relation. The shoe rest generally designated as 14 is formed of a substantially channel shaped stamping, the web portion 15 thereof, comprising the shoe rest and which preferably is formed with an irregular tractive surface which 40 may be suitably formed by the studs 16 extending 45 thereover or on limited portions thereof as desired.

The width of the channel portion of the shoe rest is such that it fits snugly in between the arms 13, and is pivoted thereto by means of the pivot 17 which passes through the arms at a 50 point preferably adjacent the base member 10 and through the downwardly extending flanges 18 of the shoe rest member. The ends 19 of the 55 flanges 18 abut against the base 10 to hold the

shoe rest extended substantially horizontally but may be cut at an angle of slightly less than 90° so that when the shoe rest is unfolded it may rest at an angle slightly lower than horizontal. The forward edges 20 of the flanges 18 are preferably cut at an appreciable angle extending in a direction from the outer edge of the shoe rest toward the base so as to permit the easy withdrawal of a shoe polisher or brush retained between the flanges 18 as will be hereinafter described.

The flanges 18 are provided with the longitudinal inwardly extending depressions 21, and as the entire shoe rest channel member is formed of a stamping of sheet metal, these side flanges 15 are somewhat expansible or yieldable. The channel with the aid of its flanges and the longitudinal depressions thereof is adapted to receive and nest a shoe polisher or brush, the back or holder portion of which substantially conforms 20 to the width between the flanges. For example, the shoe polisher 22 having the hand-gripping indentations 23 extending along the side edges of the back holder portion may be inserted between the flanges 18 with the bristles or soft polishing 25 surface 24 extending inwardly adjacent the web 15, so that the longitudinal depressions 21 set into the hand grip depressions 23 and thereby slidably receive the shoe polisher or brush and retain it. It will also be readily seen that the 30 depressions 21 can also act as gripping members and can also receive a shoe polisher or brush which does not necessarily have a hand gripping portion, and that the depressions on the flanges 35 may be replaced by bowed strip springs or the like.

In order to limit the movement of the shoe polisher or brush between the flanges of the shoe rest or to prevent its dropping therefrom when the device has been folded to its horizontal position, suitable fingers or indentations 25 may be provided on the flanges adjacent their ends 19. In order to hold the device locked in its inoperative horizontal position suitable clamping or engaging means may be provided to hold the shoe 45 rest channel 14 locked between the arms 13. This may be accomplished by means of complementary projections and recessions such as projections 26 extending inwardly of the arms 13 and the recessions or perforations 27 on the 50 flanges adjacent their ends 19, or vice versa.

As hereinbefore set forth, due to the slight resilience of the stampings which form the component parts of this device, the shoe rest may be raised from its extended position shown in Fig. 2 55

to the inoperative position shown in Fig. 1 by lifting the shoe rest and pressing it towards the attaching base so as to cause the projections 26 to snap into the depressions 21. To extend the device to its operative position a slight downward urging of the shoe rest channel will be sufficient to disengage it from the cooperative snapping portions 26 and 27. It will thus be seen that as soon as the elements are unlocked from their snaps the shoe rest immediately turns about its pivots and drops by gravity to its extended and operative position where it remains firmly by reason of the abutting action of the ends 19 against the base 10 where it rests and is firmly supported in a fixed position. To close the device it is merely necessary to raise the channel either by the hand or by the foot to its horizontal position where it will be snapped and held until further use.

Although I have in the foregoing set forth the preferred embodiment of my invention, it will be readily apparent to one skilled in the art that various changes in the details thereof may be made without departing from the spirit of my invention, and I therefore do not wish to be restricted thereto except as so limited by the appended claim.

I claim as my invention:
An article of the class described, comprising a

relatively short base adapted for vertical mounting attachment and formed with a pair of horizontally spaced apart parallel perpendicularly extending arms, and a shoe rest mounted between said arms and in pivotal engagement therewith about a fixed axis, the said shoe rest being substantially in the form of a channel and of greater length than said base, the outer web face thereof being formed with a tractive surface, the flanges thereof extending downwardly and being formed with a longitudinal inwardly extending depression terminating at one edge in inwardly struck stop fingers and adapted to slidably receive and hold nested a shoe polisher formed with complementary slots along the sides of the back handle portion thereof, the said arms and flange ends adjacent thereto being formed with a means to lock the shoe rest in vertical inoperative position, the flange edges being arranged and adapted to co-act with the base to maintain the upper surface of the shoe rest at an angle to the horizontal, the flange faces adjacent the outer end of said foot rest being partially cut away in tapering relationship to the forward edge thereof to expose a portion of the shoe polisher back to adapt it to be readily withdrawn from nested position.

FRANK B. WILLIAMS.
